UNITED STATES PATENT OFFICE.

JAMES ATKINSON, OF MELLOR, ENGLAND.

STEAM-TURBINE.

No. 902,797.

Specification of Letters Patent.

Patented Nov. 3, 1908.

Application filed January 16, 1908. Serial No. 411,150.

To all whom it may concern:

Be it known that I, JAMES ATKINSON, a subject of the King of Great Britain and Ireland, and resident of Mellor, in the county of Derby, England, engineer, have invented certain new and useful Improvements in Steam-Turbines, of which the following is a specification.

This invention relates to improvements in steam turbines and particularly to those having a plurality of or multiple stages of expansion and whether of the reaction or impulse type, the object being to provide means for governing them and for controlling the action of the working fluid in such a manner that a portion of the latter may be reemployed in conjunction with the further supply of fresh or boiler steam, after it has given out a portion of its energy to the rotor, thereby reducing the total amount of steam formerly required to be generated for developing a given power in the turbine.

Prior to the date of my invention various methods have been used for governing the power and speed of steam turbines, a common arrangement being to throttle the steam admission. This is largely used because of its simplicity although it is well known that it causes considerable loss on medium or light loads owing to the drop between the boiler pressure and that at which it enters the turbine, this drop being very largely wasted so far as power production is concerned. I utilize this drop of pressure in the fresh steam and by means of one or a plurality of suitable injector nozzles, arranged and adjusted to suit the conditions of working at the time, draw partially expanded steam back, from the turbines say, from about midway between the inlet and the exhaust, and force it into the turbine again combined with the fresh steam. The steam thus drawn back is hereinafter called the induced steam and as it adds to the volume of the total steam passing through the earlier stages of the turbine it reduces the amount of fresh steam required as already stated. Turbines may also be specially constructed to work under average conditions with reduced inlet pressures and considerable quantities of induced steam, the relatively high boiler pressure being economically employed in raising the pressure of the partially expanded induced steam while the reduced inlet pressure makes it possible to run economically at lower speeds or with fewer

stages in the turbine. As the earlier stage of such turbine would have a larger area than in turbines as ordinarily constructed, the blades would be longer and there would be less leakage.

To enable my invention to be clearly understood I append a sheet of drawings in which

Figure 1 shows steam diagrams illustrating the principle of working and Fig. 2 a turbine in vertical section constructed in accordance therewith.

In the steam diagrams shown in Fig. 1 the toes of the diagrams are not fully shown, portions being broken out so that the rest may be on a larger scale. The large sized diagrams $a b c d$ represent the amount of power in a certain weight of steam at a pressure of 165 lbs. per square inch absolute, expanded down to a low pressure, say 1½ lbs. absolute. If this steam was admitted at full pressure to the inlet of, say, a "Parson" type of turbine it would represent the theoretical energy in this weight of steam. The other diagrams show smaller weights of steam admitted to the turbine when running at lighter loads and being wiredrawn at admission. For instance, if the weight of steam is throttled down to one half, the turbine running at a correspondingly reduced load, the initial pressure at the inlet would probably be in the neighborhood of 100 lbs. absolute and an amount of energy represented by the area of the four-sided figure $a b^2 e^2 a^2$ would be almost entirely lost so far as power production is concerned and $a^2 e^2 c d$ shows the available power left.

If the fresh steam is passed through a suitable injector nozzle or nozzles, adjusted in relation to a properly constructed induced steam nozzle, having a communication with the turbine at a place where the steam has been expanded to, say, 20 lbs. absolute, a certain amount of induced steam can be drawn out of the turbine at this place, raised to the 100 lbs. and again forced into the turbine to assist in driving it. The amount of the induced steam so drawn back is represented by the line $h^2 g^2$, when at 20 lbs. pressure, or by the line $e^2 f^2$ at the 100 lbs. pressure, and the four-sided figure $e^2 f^2 g^2 h^2$ represents energy recovered by the injector action of the steam falling from the 165 lbs. to the 100 lbs., being, of course, less than the area $a b^2 e^2 a^2$ owing to eddy and friction losses in the nozzles. The greater the ef-

iciency of the nozzles, however, the more nearly the area of $e^2 f^2 g^2 h^2$ will approach to the area $a b^2 e^2 u^2$ and the larger the proportion of otherwise wasted energy recovered.

5 The other diagrams in Fig. 1 show other proportions of fresh boiler steam throttled down when admitted to the turbine in the one case, or the energy available for drawing in induced steam and the volume of induced steam drawn in in the other case. It must be understood that the various pressures and quantities are necessarily only approximate.

My invention may be applied to any kind 15 of turbine either of the reaction or of the impulse type, so long as it has more than one stage of expansion or to turbines as ordinarily constructed, say to one of the "Parson" type, in which the greater loads and 20 overloads are carried by admitting full boiler pressure initially to the blades of the turbine, with perhaps a by-pass for the greatest loads; the initial pressure decreasing with the load when the injector nozzles 25 come into action and draw back induced steam, thus obtaining increased economy on these lighter loads. It may also be applied to specially-constructed turbines working on full loads with reduced inlet pressures 30 and some induced steam.

Fig. 2 shows a specially-constructed turbine arranged to work with full loads with an appreciable proportion of induced steam and having some considerable advantage 35 over a turbine as usually constructed. In this arrangement the fresh steam at full boiler pressure enters at i passes down through the movable nozzle l arranged in the casing u , which in conjunction with the 40 fixed inner cone m , causes it to issue in a regulated circular jet, at n which induces steam from the turbine at k through the pipe connection p after it has done some work and is partially expanded, raising its pressure 45 and causing it to reenter the turbine at the inlet j , mixed with fresh steam; the pressure of the mixture being regulated by the position of the movable nozzle l , which in its lowest position admits full boiler pressure 50 sure through inlet j .

The relative adjustments of the nozzles may be made by hand, more particularly in marine turbines, or by means of any suitable governor u' , with or without a relay power 55 for moving the somewhat heavy parts which may in some instances be necessary. The inner cone m may be adjusted to suit the best conditions of working by means of a suitable distance washer r .

60 More than one set of nozzles suitably disposed may be used in a turbine, more particularly if of considerable size.

Turbines of the "Parson" type very commonly have the rotor constructed with three 65 diameters, a small diameter at the high pres-

sure end, an intermediate diameter and a large diameter at the low pressure end. They can, however, be satisfactorily constructed on this principle with one diameter only, as owing to the low initial pressure the 70 rings of blades at the high pressure end are not required and those on the intermediate diameter, having a greater volume of steam passing through them, require to be increased in area, consequently they may conveniently 75 be increased in diameter and made the same as those at the low pressure end. Owing to the reduced number of stages required, the turbine is considerably shortened and as the rotor o may be constructed of one diameter, 80 requiring only one balancing piston s , the cost of construction is materially reduced. For the same reason smaller or slower-running turbines can be economically constructed, the increased area through the earlier 85 rings of blades making it possible to use longer blades so that leakage loss is reduced.

In marine turbines it is very usual to employ a high pressure unit working with one or two low pressure units. In such instances 90 the induced steam may be taken from the system, say, after passing through the high pressure unit, or it may be taken from part way along the low pressure unit or units. In turbines of one or of several units also, it may 95 be drawn from the system at any desired stage of expansion. It is not desirable to take the induced steam from the turbine too late in the expansion as this would necessitate large connections and the injector nozzles might not be so efficient, on the other hand it should not be taken too early as it would not have been expanded sufficiently 100 to have allowed it to have given up much power before being withdrawn. When applied to turbines working non-condensing the induced steam may be taken from the exhaust. It will be understood that with this system a greater weight of steam will 105 usually be passing through the high pressure portion than through the low pressure portion, as however, it is frequently difficult to get as much area through the low pressure as might be desired, no disadvantage will arise 110 from this cause.

Very high boiler pressures may be used with these turbines, the turbines themselves operating with a moderate range of pressures and not requiring to have an excessive number of stages, thus obtaining the economy 115 due to the higher pressure without incurring the usual disadvantages.

For marine purposes the turbines can be conveniently and economically regulated for speed or power and special cruising turbines 120 for slow speeds may not be required. They could also be used in lower speed vessels than those to which the present type of turbine is practically confined.

The induced steam may be dried or heated 130

before passing to the injector nozzles in any convenient manner, say, by means of a tubular heater supplied by fresh boiler steam. Also the combined fresh steam and induced steam may be similarly heated before passing through the turbine.

What I claim as my invention and desire to secure by Letters Patent is:—

1. In a steam turbine, the combination, 10 with a cylinder provided with a conical and annular inlet-passage terminating in a jet-pipe which is connected to the portion of the cylinder in which high pressure steam is used, of a pipe connected at one end to another 15 portion of the said cylinder in which partially expanded steam is used, said pipe being connected at its other end with the inlet end portion of the said conical inlet-passage, a supply-pipe for high pressure steam, a nozzle 20 operatively connected with the said supply-pipe and having its outlet end arranged in the said conical inlet-passage, and means for sliding the said nozzle longitudinally of the said conical inlet-passage to adjust the ratio of high pressure and low pressure steam supplied to the said jet-pipe.

2. In a multiple-stage steam turbine a 25 variably-adjustable injector nozzle located

in the steam inlet and communicating with the turbine cylinder an induced steam pipe 30 connection from the cylinder to the nozzle, a spindle coupled to the movable part of the injector nozzle and means for mechanically connecting the injector nozzle with a governor operated from a suitable part of the ordinary turbine mechanism substantially as and for the purpose described.

3. In a multiple-stage steam turbine consisting of a plurality of units, a variably-adjustable injector nozzle located in the steam 40 inlet and communicating with the turbine cylinder and induced steam pipe connection between any one of the units communicating with the injector nozzle, a spindle coupled to the movable part of the injector nozzle 45 means for mechanically connecting the injector spindle with a governor and a governor operated from a suitable part of the ordinary turbine mechanism substantially as and for the purpose described.

In testimony whereof I have hereunto set my hand in the presence of two witnesses.

JAMES ATKINSON.
